UNITED STATES PATENT OFFICE

146,270

DESIGN FOR A CASING FOR CIGARETTE LIGHTER

Harold J. Sudbrink, Woodside, N. Y.

Application May 4, 1945, Serial No. 119,401

Term of patent 3½ years

(Cl. D48—27)

To all whom it may concern:

Be it known that I, Harold J. Sudbrink, a citizen of the United States, residing at Woodside, in the county of Queens and State of New York, have invented a new, original, and ornamental Design for Casing for Cigarette Lighter, of which the following is a specification, reference being had to the accompanying drawing, forming a part thereof.

In the drawing:

Fig. 1 is a side view of a casing for cigarette lighters, showing my new design;

Fig. 2 is a plan or top view of the same.

The characterizing features of my design reside in the configuration and surface ornamentation of the cap, and in the co-operating curved edges of the cap and body elements, all as shown.

The sides not shown are identical with the one shown, and the bottom is plain.

I claim:

The ornamental design for a casing for cigarette lighter, as shown and described.

HAROLD J. SUDBRINK.
